Attorney

UNITED STATES PATENT OFFICE

MATTHEW J. BRUNNER, OF BUFFALO, NEW YORK

CURTAIN FIXTURE

Application filed May 14, 1930. Serial No. 452,209.

This invention relates to improvements in curtain fixtures and has for its chief object the provision of simple and effective means for detachably coupling the rod to its supporting brackets.

Another object of the invention is to provide a curtain fixture which is inexpensive in construction, which is neat in appearance, and which is so designed as to effect the ready 10 application and removal of the rod to and from its brackets, the latter embodying self-contained latching elements for interlocking engagement with the rod.

In the accompanying drawings:—

15 Figure 1 is a fragmentary front view, partly in section, of a curtain fixture embodying my invention. Figure 2 is a top plan view thereof, partly in section. Figure 3 is an enlarged cross section on line 3—3, Figure 1.

20 Figures 4 and 5 are perspective views of the bracket and a portion of the curtain rod. Figure 6 is a fragmentary top plan view of a different type of curtain rod embodying my invention.

25 Similar characters of reference indicate corresponding parts throughout the several views.

In the embodiment of my invention shown in Figures 1 to 5 inclusive, 10 indicates the 30 top strip of a window casing to which the curtain rod 11, which may be extensible, is attached by brackets 12. The rod shown is of the sectional flat bar type having rearwardly bent lips or flanges 13 at its upper 35 and lower edges which are adapted to telescopically fit one within the other, the outer ends of the rod-sections being adapted to slidingly fit over the brackets.

Each bracket 12 has a rod-receiving arm or 40 portion 14, which, in this instance, is parallel to the window-casing and spaced therefrom by a transverse connecting web 15 projecting outwardly from the attaching base of the bracket, as seen in Figures 2 and 4. The rod-engaging arm and its connecting web have 45 an intercommunicating longitudinal slot 16 which terminates at one end adjacent the free end of said arm and at its other end at the base of the bracket, as clearly shown in Figure 4, to form upper and lower guide mem-

bers for receiving the corresponding flanged edges of the rod 11. While the resulting lower portion of the bracket-arm 14 and its web are fixed or integrally joined with the base of the bracket, the upper portion is disconnected from the base, as seen in Figures 3 and 4, to form a yieldable latching element 17 which is free to yield or be displaced vertically in the plane of the arm toward and from the lower portion thereof. In its top edge, 55 the longitudinal portion of this latching element has a locking tooth or projection 18 engageable with an opening 19 formed in the flanged upper edge of the curtain rod adjacent its end. The transverse portion of the 60 latching element has a finger piece 20 formed thereon by which the same may be forced downwardly to release its locking tooth from the rod-opening, as indicated at the right hand end of Figure 1. This tooth is preferably sloped at one side and more or less abrupt at its other side to enable the rod to be automatically interlocked therewith by merely slipping it over the bracket-arm and prevent accidental displacement of the parts 65 in their latched position, respectively.

In Figure 5, I have shown my invention in connection with a different type of curtain rod 21, one which projects outwardly a greater distance from the window casing 80 than the type or rod previously described. In this case the rod-engaging arm of the bracket 22 is disposed at right angles to the window casing, but otherwise the construction of this bracket is practically the same 85 as that described in the former type.

This improved fixture, while manifestly simple and compact in construction and is producible at a moderate cost by a stamping operation, insures a positive and reliable 90 connection of the rod to the brackets; it is durable, and the latching means being a self contained part of the bracket is always in place for use. Furthermore, this combined bracket and latching element is capable of 95 use with present day rods now in common use without altering their construction.

I claim as my invention:—

1. In a curtain fixture, a bracket having a supporting arm consisting of spaced guide 100

- members connected at their free ends for cojointly receiving a curtain rod in telescopic relation thereto, one of said guide members being fixed to the bracket and the other being detached therefrom and yieldable in the plane of said arm for interlocking engagement with the rod, the detached end of said yieldable arm having a projection disposed beyond the rod-engaging portion thereof.
5. 2. In a curtain fixture, a bracket having an attaching base and a supporting arm projecting therefrom, for receiving a curtain rod, said arm having a longitudinal slot therein extending from a point adjacent its free end to said base, one of the resulting arm-portions defined by said slot constituting a latching element for interlocking engagement with the rod and having an extension displaced out of the plane of the arm for shifting the latching element from an engaged to a released position.
10. 3. A bracket for curtain rods, comprising an attaching base, and a longitudinally-slotted arm projecting from said base, one of the resulting arm-portions defined by the slot being detached from the base to form a latching element movable toward and from the companion arm-portion and having a locking projection in the plane of the arm and a terminal projection displaced laterally therefrom.
15. 4. A bracket for curtain rods, comprising an attaching base, and a longitudinally-slotted arm projecting from said base, one of the resulting arm-portions defined by the slot being detached from the base and being yieldingly movable toward and from the companion arm-portion to constitute a latching element, said first-named arm-portion having a locking tooth thereon and a finger piece for shifting such arm-portion from an engaged to a released position.
